(57) CLAIM

The ornamental design for a display screen with user interface for an advertisement management application, as shown and described.

DESCRIPTION

FIG. 1 is a view of a graphical user interface for a first embodiment of an advertisement management application, the view showing a first image in a first sequence; FIG. 2 is a second image in the first sequence; FIG. 3 is a third image in the first sequence; and FIG. 4 is a fourth image in the first sequence.

FIG. 5 is a view of a graphical user interface for a second embodiment of an advertisement management application, the view showing a first image in a second sequence; FIG. 6 is a second image in the second sequence; FIG. 7 is a third image in the second sequence; and FIG. 8 is a fourth image in the second sequence.

FIG. 9 is a view of a graphical user interface for a third embodiment of an advertisement management application, the view showing a first image in a third sequence; FIG. 10 is a second image in the third sequence; FIG. 11 is a third image in the third sequence; and, FIG. 12 is a fourth image in the third sequence.

The broken lines illustrate a portion of a display screen and other elements of the user interface that form no part of the claimed or the claimed design.

With respect to the sequences shown in FIGS. 1-4, 5-8, and 9-12, the process or period in which one user interface transitions to another user interface forms no part of the claimed design.
